Container Corporation of America, Chicago, Ill., a
corporation of Delaware

Filed Feb. 12, 1958, Ser. No. 714,796

1 Claim. (Cl. 206—65)

This invention relates to article packaging means and particularly to paperboard cartons constructed and arranged to hold a plurality of fragile articles in fixed position during shipment, such position being advantageous for display purposes.

Present day packaging methods are directed not only to the transporting of merchandise in a safe, compact, and economical manner, but in many instances must provide for inspection or display features therewith to facilitate sales of the merchandise at a retail level. This is particularly true with respect to fragile or ornamental articles, which because of their nature are more salable when viewed and examined by the prospective purchaser.

Accordingly, it is an important object of the present invention to provide a carton suitable for retaining and supporting articles placed therein in a fixed position during shipment, which position affords adequate display of the article and inspection thereof without necessitating removal of the article from its fixed position.

Another object of this invention is to provide a shipping and display carton of the type described wherein the articles packaged are supported centrally interiorly of the carton and are not directly supportingly engaged by the carton walls.

A further object of this invention is to provide a shipping and display carton formed from a single blank, constructed and arranged to afford multi-ply side and end walls, and a centrally disposed article supporting member.

A still further object of this invention is to provide a shipping and display carton as described which can be partially assembled to afford a sufficiently rigid structure suitable to permit production line loading of the carton and complete assembly thereafter.

To achieve the foregoing objects it is contemplated that a single blank of bendable material, as paperboard, can be properly cut and scored to provide a plurality of panels hingedly connected in side-by-side relation, formable to afford multi-ply side walls with an article supporting member disposed therebetween and parallel therewith, and flap extensions from particular panels, formable to provide multi-ply end walls. The blank is designed to permit erection of adjacent central panels into an inverted V-shaped supporting member, having aligned and complementary cut out portions adapted to receive the articles to be packaged. After disposition of the articles in said support member, set-up and assembly of the remaining panels with interpositioning and securing of the flap extensions, provides multi-ply side and end walls which enclose and fix the articles in position. In such position the articles are well-supported and protected for shipment, and are suitably exposed for display and inspection purposes without removal of the articles from their position of support.

Further objects, features, and advantages of this invention will appear or be apparent to one skilled in the art from the following description, reference being made to the accompanying drawings, in which:

Figure 1 is a plan view of the one-piece blank from

2

which the shipping and display carton is formed, having portions thereof broken away and parts of the blank folded in pre-setup assembly.

Figure 2 is a transverse sectional view of the blank, shown in partial assembly and having an article supported therein.

Figure 3 is a transverse sectional view similar to that of Figure 2, but showing a condition approaching complete assembly.

10 Figure 4 is a front elevational view on an enlarged scale of a completely assembled and set-up carton.

Figure 5 is a horizontal sectional view taken on line 5—5 of Figure 4, but with the packed articles not shown.

15 Figure 6 is an enlarged vertical sectional view taken on line 6—6 of Figure 4.

Figure 7 is a vertical sectional view taken on line 7—7 of Figure 6.

Figure 8 is a perspective view of an assembled carton, but without articles packed therein.

Figure 9 is a perspective view of an assembled carton shown partially inserted within a sleeve type overwrap.

Referring now to the drawings and particularly Figure 1, reference numeral 10 indicates generally a sheet of suitable material, such as paperboard, cut and scored to provide a one-piece blank, bendable, in a manner to be described, to form a carton adapted for the purposes herein set forth. As shown, the blank is formed to provide serially connected main panels 14, 16, 18, 20, 22, 24, 26, and 28, hingedly connected at scorelines 15, 17, 19, 21, 23, 25, and 27, respectively. Panels 14 and 16 are formed to provide at each end thereof flap extensions 30 and 32, respectively, hingedly joined one to the other along the scoreline 15, and suitably hingedly connected to their respective panels by scorelines 31 and 33. End panel 28 is formed to provide at each end thereof flap extensions 36, hingedly connected to said panel along scorelines 37. The central adjacent panels 20 and 22 are formed to provide at each end thereof and hingedly connected thereto, flaps 40 and 42, respectively, said flaps being of triangular shape and complementary, in a manner and for a purpose to be described.

The blank 10 as thus far described is symmetrical, but as pointed out in the description of Figure 1, and for purpose of explanation, portions of the blank have been broken away and are shown in a pre-setup condition. 45 Thus, as viewed in Figure 1, the lower portions of panels 14, 16, 26, and 28 have been manipulated to illustrate the first step in fabrication of a shipping and display carton according to the teachings of this invention. This first step involves folding the panels 14 and 28 downwardly about their respective scorelines 15 and 27 to a position of abutment with the adjacent panels 16 and 26, respectively. As shown, the undersides of panels 14 and 28 are provided with adhesive coatings 45 and 47, respectively, which secure the panels 14 and 16, and the panels 26 and 28, in this abutting or face-to-face position. Insofar as the panels 14 and 16 are secured one to the other, it should be noted that the flap extensions 30 and 32, though disposed in a similar face-to-face relationship, are not provided with an adhesive therebetween and thus are not secured together, the purpose of which will be described later. Also, as shown in Figure 1, the central adjacent panels 20 and 22 are formed to offer a plurality of oval-shaped openings 50 and 52, respectively, openings 60 50 being larger than the openings 52, for a purpose also to be described later.

As best seen in Figure 2, the pre-setup blank described can be manipulated to buckle the adjacent central panels 20 and 22 upwardly to form an inverted V-shaped member. In such position, the triangular-shaped flaps 40 and 42 at each end of the panels 20 and 22, respectively, are folded one upon the other and secured in any suit-

able fashion together, thereby maintaining panels 20 and 22 in the inverted V shaped disposition shown. It is noted that the flaps 40 and 42 are shaped in a complementary manner whereby to position and fix the panels 20 and 22 angularly relatively one to the other so as to align the openings 50 and 52, as seen in Figure 5. In such position, panels 20 and 22 afford an article supporting member, and as shown in the preferred embodiment, the aligned openings 50 and 52 are designed and do accommodate a tapered tumbler, indicated by the reference numeral 55.

After loading, i.e., disposition of tumblers in the inverted V shaped support member, complete assembly of the carton can be accomplished, in the following manner. Flap extensions 30 and 32 in face-to-face relationship, are folded as a unit upwardly about their respective scorelines 31 and 33 to a disposition normal to the secured panels 14 and 16; likewise, flap extensions 36 are folded upwardly about their scorelines 37 to a disposition normal to the secured panels 26 and 28. With the flap extensions in the positions described, upward movement of secured panels 14 and 16 about the scoreline 17, and upward movement of secured panels 26 and 28 about the scoreline 25 will result in pivotal movement of flaps 30 and 32 and flap 36 inwardly, see Figure 3. As shown in Figure 3, it is contemplated that such pivotal movement of the flap extensions will include disposition of flap 36 between the integrally connected and adjacent flaps 30 and 32. To facilitate the interpositioning of flap 36 between the flaps 30 and 32, the upper leading corner of said flap 36 is of arcuate shape, indicated by numeral 56, and in an obvious manner will cam against the connecting portion between the flaps 30 and 32 to promote complete inspection of flap 36 therebetween. Upon erection of the secured panels 14 and 16, and secured panels 26 and 28 to a position normal to the adjacent panels 18 and 24, respectively, interposition of the flap extensions is complete. The carton thus assembled is maintained in this condition by securing of the flap extensions one to the others, in any suitable manner, as by staples 58.

Figure 4 illustrates clearly the display and inspection features obtained by construction of a carton according to the teachings of this invention. It can be seen that this carton construction affords maximum viewability of the glass tumblers 55 without necessitating removal of the tumblers from their fixed position of support. Also, it is appreciated that the bendable quality of the carton material, in this instance paperboard, will permit distortion outwardly of the multi-ply side wall, comprising secured panels 14 and 16, and secured panels 26 and 28, sufficiently to allow adequate inspection of the tumbler rim and bottom surfaces. Also, it is contemplated that in the case of packed cylindrical articles, as tumblers, said articles can be rotated for inspection purposes, without removal from the position of support. It is noted that the display and inspection features available with this carton do not require removal of the packed articles from the carton, and, in fact, the construction shown prevents removal of said articles without partial destruction of the carton. In this respect, the carton is considered pilfer-proof.

Referring now to Figures 6 and 7, it can be seen that the article supporting member, comprising panels 20 and 22, is not directly supportingly engaged by either the multi-ply side walls, comprising secured panels 14 and 16, and secured panels 26 and 28, or the multi-ply end walls, comprising flap extensions 30, 32 and 36. The positioning and support means for the inverted V shaped support member reside in the narrow base panels 18 and 24. Thus, while the article supporting panels 20 and 22 are rigidly relatively held by the secured triangular flaps 40 and 42, the entire support member, including the tumblers disposed therethrough, is movable

relative to the side and end walls through the resiliency afforded by the connecting panels 18 and 24. This resiliency, though involving only slight distortion or movement of said connecting panels and subsequently the support member, is nevertheless sufficient to absorb and dissipate many shocks or blows, particularly those directed to the corners of the carton, adequately to prevent fracture and breakage of fragile packed articles, such as the tumblers 55.

Also directed to the protection of articles packed, particularly those of a fragile nature, is the provision of multi-ply side and end walls constructed as previously described. As shown, the carton side walls comprise secured panels 14 and 16 and oppositely disposed secured panels 26 and 28, and the end walls each comprise flap extensions 30, 32 and 36. Thus, the side walls are double-ply and the end walls are triple-ply, all of which offers a sturdy carton providing excellent insulation for the articles packed therein. In addition, it is contemplated that the assembled and setup carton will be overwrapped for shipping purposes. As shown in Figure 9, a preferred form of overwrap would be a sleeve or tubular member 60, which in combination with the described carton disposed therein would affect triple-ply side walls.

From the foregoing description it is apparent that a single blank of bendable material suitably cut and scored can be formed to provide a carton having multi-ply side and end walls and a centrally disposed article supporting member, the construction being such that partial assembly of the carton permits disposition of articles in the support member and complete assembly locks the carton in a manner preventing removal of the articles. In such condition the articles while adequately exposed for display and inspection purposes, are nevertheless supported in a compact and resilient manner affording complete protection of the articles for shipping purposes.

While the foregoing description sets forth the invention in specific terms and in conjunction with a preferred embodiment, it is to be understood that many variations and modifications may be resorted to without departing from the broad aspects of the invention as defined in the appended claim.

Having described the invention, what is claimed is:

A display carton formed from a single blank of suitable sheet material such as foldable paperboard, comprising: a pair of co-planar bottom wall panels having mutually facing parallel inboard edges spaced transversely from each other on opposite sides of the longitudinal vertical center plane of the carton; a pair of side walls hingedly attached to and upstanding vertically from outboard edges of respective bottom wall panels, each of the side walls including a pair of similar inner and outer panels hingedly interconnected at their upper edges and lying in juxtaposition with each other; end closure flaps hingedly attached to the ends of certain of the side wall panels and connected to each other to close the ends of the carton; and an article supporting member disposed between said bottom wall panels, said member including a pair of upwardly converging panels hingedly interconnected at their upper edges and hingedly attached at their lower edges to the inboard edges of respective bottom wall panels, said member panels having aligned openings for receiving and floatingly supporting an article independently of the side walls and ends of the carton.
